UNITED STATES PATENT OFFICE.

HENRY LUEDINGHAUS, JR., OF ST. LOUIS, MISSOURI.

DUMPING-WAGON.

1,158,138.

Specification of Letters Patent. Patented Oct. 26, 1915.

Application filed March 1, 1915. Serial No. 11,191.

To all whom it may concern:

Be it known that I, HENRY LUEDINGHAUS, Jr., a citizen of the United States, residing at St. Louis, Missouri, have invented a certain new and useful Improvement in Dumping-Wagons, of which the following is a full, clear, and exact description, such as will enable others skilled in the art to which it appertains to make and use the same.

This invention relates to dumping wagons, and has for its main object to provide a dumping wagon of novel design whose body is composed of a pair of longitudinal divided sections, one or both of which are adapted to be moved upwardly so as to discharge the load through the space formed between said sections when they are separated or moved apart.

Another object is to provide a dumping wagon of the character described that comprises a novel means of simple construction for actuating the movable sections of the body and for securely holding said sections closed. And still another object is to provide a serviceable and inexpensive dumping wagon which is of such design that it can be used successfully for conveying a substance which is of a more or less liquid character. Other objects and desirable features of my invention will be hereinafter pointed out.

Figure 1 of the drawings is a perspective view of a dumping wagon constructed in accordance with my invention. Fig. 2 is a cross-sectional view through the body of the wagon, showing the sections of the body separated; and Fig. 3 is a top plan view of a portion of the body, illustrating part of the operating mechanism for the movable sections of the body.

Referring to the drawings, which illustrate the preferred form of my invention, A designates the frame of the wagon, which may be of any preferred form, and B designates the body, which preferably consists of two sections 1 that are divided longitudinally of the body at the center line of same. The body B is preferably of approximately semi-cylindrical shape in cross section so that each of the sections 1 consists of a substantially segmental member. Said sections 1 are hinged or pivotally mounted in such a manner that they can be swung upwardly about a horizontally disposed axis located at the longitudinal center of the body, and means are provided, for raising and lowering said sections and for securely locking

said sections in their closed position. In the form of my invention herein shown the two sections 1 are supported by a shaft 2 that extends longitudinally of the body and which is carried by uprights on the frame A of the wagon. Any suitable kind of uprights may be used for supporting the shaft 2, but I prefer to use uprights 3 that are substantially inverted V-shaped and each of which is formed from a bar of iron that is bent to form a bearing 3^a at the upper end of the support or upright in which the shaft 2 is rotatably mounted. At the lower end of the diverging legs of the upright are laterally projecting flanges 3^b which are secured to the end sill 4 of the frame A, it, of course, being understood that each end sill of the frame is provided with an upright 3 so as to firmly support the opposite ends of the shaft 2 and hold said shaft in a horizontal position.

The two sections 1 of the body are suspended from the shaft 2 by means of hangers 5 secured to the ends of said sections 1 at the inner upper edges of same, as shown in Fig. 3, thereby enabling the sections 1 to be swung upwardly about the shaft 2 as an axis, so as to discharge the load through the space formed by separating said sections, as shown in Fig. 2.

Any suitable means may be employed for raising and lowering the sections 1 of the body, and while I prefer to use an operating mechanism of substantially the construction herein shown on account of its strength, simplicity and efficiency, I wish it to be understood that it is immaterial, so far as my invention is concerned, what particular means is employed for operating the sections 1 of the body so as to discharge the load and to restore said sections to their normal closed position. The operating mechanism of the construction herein shown consists of two winding shafts 6 that are rotatably mounted in bearings 7 on the end sills 4 of the frame A of the wagon, sets of chains or other suitable flexible members 8 and 8^a connected to the winding shafts 6 and to the sections 1 of the body, and means for rotating both of said winding shafts 6 simultaneously in one direction so as to cause the chains 8 to be wound thereon, and thus swing the sections 1 of the body upwardly and to rotate said shafts 6 in the opposite direction, so as to cause the chains 8^a to be wound onto same and thus move the sections 1 downwardly.

and securely lock them in their closed position.

The means herein illustrated for rotating the winding shafts 6 consists of a sprocket chain 9 that passes around sprocket wheels 10 on the winding shafts 6 and also around a sprocket wheel 11 on one end of the horizontally-disposed shaft 2 that sustains the two sections of the body, said shaft 2 being provided at one end with a hand wheel 12, so as to enable it to be rotated first in one direction, to raise the sections 1 of the body, and then in the opposite direction, to lower said sections.

15 A locking device consisting of a pivotally mounted pawl 13 on the upright 3 and a co-operating ratchet wheel 14 on the shaft 2 serve to prevent accidental retrograde movement of the shaft 2, after said shaft has been 20 rotated in the direction to raise the sections 1 of the body.

When the sections 1 of the body are in their normal closed position gravity and the pull that the chains 8^a exert on said sections 25 prevent them from opening accidentally.

The body B may be formed of any suitable material and may be of any preferred construction. I prefer, however, to provide each section 1 of the body with an iron frame, preferably formed from strips of angle iron, so as to produce an exceptionally strong and rigid frame at a low cost. The end walls 15 of the sections 1 and the curved bottom and side wall 16 of each of said sections are preferably arranged on the inside of said frame so that they will be supported by the flanges thereof. In the wagon herein shown the curved bottom and side wall 16 of each section of the body is formed 30 from narrow tongue and groove boards, but it will, of course, be understood that this wall could be formed from sheets of metal. In order to insure tight joints between the meeting edges of the sections 1, and thus 35 enable the wagon to be used for conveying substances of a more or less liquid character, I have provided the lower edge and the end walls of one section of the body with a rib 17 that fits into a groove 18 on the lower edge and the end walls of the other section, said rib being formed by narrow strips secured to the angle iron frame of one of the sections, and said groove being formed by pieces of channel iron secured to 40 the angle iron frame of the other section in the manner illustrated in Fig. 2. The intermediate portion of the body B can be reinforced and strengthened by means of braces 19 whose outer ends are connected to the 45 top members of the frames of the sections 1 of the body and whose inner ends are connected to the horizontally disposed shaft 2, as for example, by being bent around said shaft. If desired, the body B can be provided with a cover of any preferred design,

so as to protect the contents of the body or prevent odors from escaping from the body when the wagon is used for conveying garbage. The wagon herein illustrated is provided with a sectional cover formed from 70 metal plates 20 that rest upon the cross braces 19 and the top flanges of the angle iron frames of the sections 1 and whose inner edges are hinged to the suspending shaft 2, as, for example, by means of bearings 20^a, 75 through which the shaft 2 passes.

A wagon of the construction above described is more efficient than the dumping wagons now in general use, owing to the fact that the load is discharged therefrom 80 by moving the two sections of the body upwardly into such a position that they do not obstruct the free discharge of the load, nor do they come in contact with a discharged load when they are restored to their normal 85 closed position. The curved form of the body and the way in which the sections of the body are mounted insure a rapid discharge of the entire load, and also enables the sections of the body to be raised and lowered easily. In addition to the desirable 90 features of the invention above mentioned, such a wagon is exceptionally strong and rigid and it can be manufactured at a low cost.

95 While I prefer to raise both sections of the body to discharge the load, I wish it to be understood that my invention is not limited to such a construction, for my broad idea consists in a body for dumping wagons 100 composed of two longitudinally divided sections having curved or inclined floors and either or both of which sections are adapted to be moved upwardly so as to form a space between said sections through which the 105 load can escape.

Having thus described my invention, what I claim, and desire to secure by Letters Patent, is:

1. A dumping wagon provided with a 110 body of substantially semi-cylindrical shape in cross section composed of two longitudinally divided portions which are so arranged that they can be swung upwardly about a common horizontal axis so as to 115 discharge the load, a horizontally disposed shaft that sustains said sections, winding shafts operatively connected to said sections so as to raise and lower same, and means for transmitting movement from said horizontally disposed sustaining shaft to said winding shafts.

120 2. A dumping wagon provided with a body of substantially semi-cylindrical shape in cross section composed of two longitudinally divided portions which are so arranged that they can be swung upwardly about a common horizontal axis so as to 125 discharge the load, a horizontally-disposed shaft that sustains said sections, winding 130

shafts operatively connected to said sections so as to raise and lower same, alining sprocket wheels mounted on said horizontally disposed sustaining shaft and on said winding shafts, and a sprocket chain that engages all of said sprocket wheels.

3. A dumping wagon provided with a body of substantially semi-cylindrical shape in cross section composed of two longitudinally divided portions which are so arranged that they can be swung upwardly about a common horizontal axis so as to discharge the load, a horizontally-disposed shaft that sustains said sections, winding shafts operatively connected to said sections so as to raise and lower same, means for transmitting movement from said horizontally-disposed sustaining shaft to said winding shafts, and means on said sustaining shaft 20 for locking the same against rotation in one direction.

4. In a dumping wagon, a frame provided with a pair of transverse end sills, uprights arranged intermediate the ends of said end

sills and provided with bearings at their upper ends, a supporting shaft journaled in said bearings, bearings arranged adjacent the ends of said end sills, a pair of winding shafts extending from sill to sill and journaled in said last mentioned bearings, a body 25 comprising a pair of longitudinally-extending, curved sections that are pivotally mounted on said supporting shaft, connecting means between said body sections and said winding shafts, connecting means between said winding shafts and said supporting shaft, means for rotating said supporting shaft so as to separate said body sections, and means for locking said supporting shaft against rotation in one direction. 30

35 In testimony whereof I hereunto affix my signature in the presence of two witnesses, this twenty-fifth day of February 1915.

HENRY LUEDINGHAUS, JR.
